(57) **CLAIM**

The ornamental design for a pajama, as shown and described.

DESCRIPTION

FIG. 1 is a front elevation view of the pajama, showing my new design;

FIG. 2 is a rear elevation view of the design illustrated in FIG. 1;

FIG. 3 is a right side view of the design illustrated in FIG. 1;

FIG. 4 is a top and left side perspective view of the design illustrated in FIG. 1;

FIG. 5 is a front elevation view of the design illustrated in FIG. 1, showing the pajama in a partially open configuration;

FIG. 6 is a top view of the design illustrated in FIG. 1; and, FIG. 7 is another front elevation view of the design illustrated in FIG. 1, showing the pajama in one of a number of different possible open configurations.

The broken lines depict stitching and form part of the claimed design.
